dian

Application November 9, 1940, Serial No. 365,016
In Germany July 20, 1939

6 Claims. (Cl. 196—53)

The present invention relates to a process for the manufacture of hydrocarbon oils.

We have found that liquid or fusible carbonaceous materials containing asphalts and hence being difficult to work up, for example, by distillation or cracking or destructive hydrogenation, for example tars, mineral oils or products of the destructive hydrogenation of coals, tars or mineral oils or pressure extracts of coals containing asphalt, may without appreciable losses be transformed into products which may easily be worked up by distillation, cracking or destructive hydrogenation and are themselves useful as Diesel oils, lubricating oils or heating oils. The process consists in subjecting the initial materials containing asphalt to a cracking under mild conditions in the presence of hydrogen, so that an appreciable proportion of the constituents boiling above 325° C. in vacuo (12 millimeters mercury gauge), say from 20 to 60 per cent, are cracked into constituents boiling between 350° C. under atmospheric pressure and 325° C. in vacuo, and the amount of constituents boiling below 350° C. under atmospheric pressure is increased at the most by about 10 per cent. This object is achieved by heating the initial materials under increased pressure, for example between 2 and 200 atmospheres or more, preferably between 3 and 100 atmospheres, in the presence or absence of hydrogen, while adding hydrogen after heating to temperatures above 400° C., as for instance between 420 and 470° C., for example in an amount of about 0.2 to about 6 cubic meters per kilogram of initial material, more particularly from 1 to 5 cubic meters or, if hydrogen be already present from the start, e. g., about 0.7 cubic meter per kilogram of initial material to avoid coking while heating, hydrogen must equally be added, for example in an amount of about 0.2 to about 4 cubic meters per kilogram of initial material, the temperature above 400° C. being maintained for a time until the above mentioned degree of cracking has been reached which may be ascertained, for example by investigating the boiling point curve of samples taken from the reaction mass. The materials are then separated into pitch and vaporous products without being released from pressure and without being cooled to any substantial extent. There is no appreciable consumption of hydrogen. The vaporous reaction products may be further worked up by destructive hydrogenation or cracking, or separated physically, especially by distillation in vacuo or by a treatment with selective solvents, or

treated with refining agents, or treated by several of these ways.

The advantage of the process according to the present invention resides in the fact that, depending on the type of the initial material, Diesel oils, lubricating oils and fuel oils may be produced without it being necessary to subject the products released from pressure to a subsequent destructive hydrogenation or cracking, the oils being obtained in higher yields and superior quality than when producing them directly by distillation under mild conditions of the initial materials. Such a distillation is attended also with the production of a substantially larger amount of asphalt than the process according to this invention. If the products obtained (after release from pressure) from the vapors by condensation are subjected to a destructive hydrogenation or cracking treatment, much larger throughputs may be used and higher yields obtained and moreover the catalysts will display a better efficiency and be active for a longer period of time than without the heating under pressure according to the present invention.

10 25 Among initial materials of the type specified above we may mention, in particular, high-boiling cracking products obtained, for example, from mineral oils, or heavy oils obtained in the destructive hydrogenation of mineral coals, pitch, 30 cracking residues or brown coals low in paraffin wax, as for example the heavy oil obtained from vapors escaping during the destructive hydrogenation. It is advantageous to add to the initial materials substances of a lower boiling point, for example middle oil, benzine, benzene or its low-boiling homologues which may be employed over again in a cycle. Products obtained in the process itself may also be added to the initial materials, especially lighter oils. Additions of the 35 said kind are not necessary if the initial material already contains sufficient amounts, for example 25 per cent and more, of low-boiling fractions. An alternative procedure consists in removing low-boiling fractions rich in hydrogen 40 which are contained in the initial materials, as for example benzene, and replacing them by low-boiling hydrocarbons lower in hydrogen, as for example benzene.

It is of advantage to add to the initial material, 45 before or during the heating, finely divided adsorption agents, as for example brown coal low temperature coke, active charcoal, natural or artificial silicates, bauxite or bleaching earths, as for example fuller's earth, or silica gel or similar porous substances or/and metal compounds, es-

pecially oxides, sulphides, phosphates or halides of the metals of the 2nd to the 8th group of the periodic system, or organic compounds, preferably those of the elements of the 5th to the 8th group of the periodic system, in amounts of from 0.1 to 10 per cent.

In practicing the process according to the present invention, the initial materials are heated to temperatures of from 400° C. to 470° C. under increased pressure, preferably under pressures of from 2 to 200 atmospheres, advantageously in a tubular heater. Part of the heated materials may be returned to the heater in order to increase the speed of flow therein, to avoid sedimentations and to save additional substances, as for example brown coal low temperature coke.

The heating may be effected with hydrogen being present already from the start. However, the hydrogen may also be added during or after the heating, but not later than when the temperature above 400° C., at which the treatment is to be carried through, has been reached. Should there be deficiency in hydrogen at this temperature, its partial pressure is to be increased, for example by adding hydrogen once or several times, the total pressure being also changed, if desired.

By a preferred method of practicing the process according to the invention the materials, after being heated in a tubular heater, are conveyed to an enlarged vessel, for example a column, without release of pressure, care being taken that the partial pressure of hydrogen prevailing in this latter vessel is higher than that prevailing in the heater. This is achieved, for example, by introducing hydrogen into the vessel at one or several points or shortly before the entry of the preheated materials. The materials may also be slightly released from pressure before entering the enlarged vessel; for example the pressure may be about 20 per cent lower than the pressure initially prevailing. The temperature in the adjoining vessel may be by about 10° to 50° C. lower than in the heating tubes. The vapor space of the enlarged vessel is advantageously equipped with baffle plates, bell trays or Raschig rings and/or such substances, as for example bauxite, silica gel or active charcoal. In this manner, with a proper choice of the temperature there may easily be accomplished a separation into vaporous products containing heavy oil which leave at the upper end of the vessel, and pitchy residues which are discharged at the lower end.

Besides hydrogen, other gases, as for example steam, gaseous hydrocarbons or gases containing the same, as for example cracking gases, furthermore oxides of carbon or nitrogen, may be added. It is especially advantageous to carry out the pressure heating under such condition that the quantity of the pitchy residue, which is usually solid at ordinary temperature and fusible, amounts to about 3 to 15 per cent and that the heavy oil contained in the vapors, which boils above 350° C. under a pressure of 760 millimeters, still contains at least 3 per cent of constituents boiling above 325° C. under a pressure of 12 millimeters. When working in this manner the effluent vapors still contain resins and asphalts which, however, have a lower molecular weight than the asphaltic constituents of the initial material and cause no trouble in the subsequent treatment.

The vapors which contain heavy oil may be treated, if desired, after being condensed with rigidly arranged or finely divided adsorption

agents of the aforesaid kind, preferably at moderately elevated temperatures, or with chemical refining agents, as for example sulphuric acid, or subjected to a refining destructive hydrogenation or a treatment with selective solvents, as for example liquefied normally gaseous hydrocarbons and/or selective solvents having a preferential dissolving power for cyclic compounds.

The process has proved especially useful in pretreating carbonaceous materials which are to be subjected to a catalytic destructive hydrogenation, for which purpose the effluent vapors together with the hydrogen contained therein may be passed over hydrogenating and/or cracking catalysts under a high pressure at temperatures of between 350° and 550° C. This destructive hydrogenation may be carried out as a cracking destructive hydrogenation, whereby low-boiling hydrocarbons are obtained, or as a so-called low temperature destructive hydrogenation, whereby lubricating oils and valuable Diesel oils are obtained. The vaporous products may also be cracked into products of lower boiling point in the presence of hydrogen which is not consumed thereby. For this purpose there are used smaller quantities of hydrogen than are usual for the destructive hydrogenation. In such cracking treatment, the catalyst may be moved through the cracking space either in the same direction as, or preferably in counter-current to, the vapors to be cracked. It is sometimes of advantage to effect a mild destructive hydrogenation after cracking, the cracking products being thus refined to a large extent.

The following example illustrates how the present invention may be carried out in practice, but the invention is not restricted to this example.

Example

Referring to the accompanying drawing which illustrates a plan for carrying out the present invention a German mineral oil is admitted through feed pipe 1 and freed from constituents boiling up to 200° C. by distillation in still 2. The distillation residue contains 35 per cent of a fraction boiling up to 350° C. under atmospheric pressure. The fraction boiling above 350° C. contains 60 per cent of constituents boiling above 325° C. at 12 millimeters (mercury gauge). The said distillation residue is withdrawn through line 3 through pump 5 and heated to 460° C. in a tubular heater 6 under a pressure of 100 atmospheres, together with 0.5 cubic meter of hydrogen per kilogram of oil, admitted through line 4, while adding through line 21 2 per cent of dusty brown coal producer ashes, the throughput per hour being 6 kilograms of oil per liter of heating space. The mixture of oil and hydrogen then passes through line 7 into an enlarged vessel 8, 3.5 cubic meters of hydrogen being added per kilogram of oil through line 8 immediately before entering this vessel. In addition, 2.0 cubic meters of hydrogen which has been preheated by means of heater 22 to 460° C. per kilogram of oil is added through line 16 in the lower part of the enlarged vessel 8.

From the lower part of the vessel 8 there are withdrawn through line 11 7 per cent of pitch together with the brown coal producer ashes added. In the upper part of the vessel 8 92 per cent of the initial material used passes into the vapor state. It contains 43 per cent of the constituents boiling up to 350° C. The waste due to formation of gas amounts to 1 per cent. The fractions boiling above 350° C. contain only 20 per cent of constituents boiling above 325° C.

under a pressure of 12 millimeters (mercury gauge).

The vaporous fractions are passed through line 12 and pump 14, together with 3 cubic meters of hydrogen per kilogram of oil, admitted through line 13 over a catalyst arranged in chamber 15 and consisting of nickel sulphide and tungsten sulphide at a temperature of 340° C. under a pressure of 250 atmospheres and subsequently over a catalyst arranged in chamber 16 and consisting of molybdenum oxide, zinc and magnesium oxide, the temperature being slowly raised from 360° to 450° C. by means of heater 17 while passing the fractions over the latter catalyst chamber 16.

The products thus obtained as passed through line 18 and fractionating tower 19. They may consist to the extent of 80 per cent of a fraction boiling up to 360 C., this fraction consisting of 25 per cent of benzine-like products boiling up to 200° C. and 75 per cent of Diesel oil boiling from 200° to 360° C. The fractions having a higher boiling point are recycled through line 20.

What we claim is:

1. The process of producing a hydrocarbon oil from a hydrocarbon mixture containing asphalt which comprises heating the initial material to a temperature above 400° C. under pressures ranging from 2 to 200 atmospheres, adding hydrogen after heating, in an amount of 0.6 to 6 cu. m. per kilogram of initial material, maintaining the initial material without appreciable consumption of hydrogen at a temperature above 400° C. until a substantial portion of the fraction boiling above 325° C. under a pressure of about 12 millimeters is cracked into a fraction boiling between 350° C. under atmospheric pressure and 325° C. under a pressure of about 12 millimeters while the fraction boiling below 350° C. under atmospheric pressure is augmented at the most by about 10 per cent, and separating the reaction product into pitch and vapors substantially without release from pressure and substantially without cooling.

2. In the process as claimed in claim 1, working in the presence of a solid adsorption agent.

3. The process of producing a hydrocarbon oil from a hydrocarbon mixture containing asphalt which comprises heating the initial material to a temperature above 400° C. under pressures ranging from 2 to 200 atmospheres in the presence of hydrogen from the start, sufficient in amount to prevent coking while heating, adding further hydrogen after heating in an amount from about 0.2 to about 6 cubic meters per kilogram of initial material, maintaining the initial material without appreciable consumption of hydrogen at a temperature above 400° C. until a substantial part of the fraction boiling above 325° C. under a pressure of about 12 millimeters is cracked into a fraction boiling between 350° C. under atmospheric pressure and 325° C. under

a pressure of about 12 millimeters while the fraction boiling below 350° C. under atmospheric pressure is augmented at the most by about 10 per cent, and separating the reaction product into pitch and vapors substantially without release from pressure and substantially without cooling.

4. The process of producing a hydrocarbon oil from a hydrocarbon mixture containing asphalt which comprises heating the initial material to a temperature between 420° and 470° C. under pressures ranging from 2 to 200 atmospheres, adding hydrogen after heating, in an amount of 0.6 to 6 cu. m. per kilogram of initial material, maintaining the initial material without appreciable consumption of hydrogen at the said temperature until a substantial part of the fraction boiling above 325° C. under a pressure of about 12 millimeters is cracked into a fraction boiling between 350° C. under atmospheric pressure and 325° C. under a pressure of about 12 millimeters while the fraction boiling below 350° C. under atmospheric pressure is augmented at the most by about 10 per cent, and separating the reaction product into pitch and vapors substantially without release from pressure and substantially without cooling.

5. The process of producing a hydrocarbon oil from a hydrocarbon mixture containing asphalt which comprises heating the initial material to a temperature above 400° C. under pressures ranging from 2 to 200 atmospheres in an elongated, comparatively narrow heating zone, passing the heated product into an enlarged adjoining reaction space maintained at substantially the same temperature, adding hydrogen in an amount of 0.6 to 6 cu. m. per kilogram of initial material, maintaining the initial material without appreciable consumption of hydrogen at a temperature above 400° C. until a substantial part of the fraction boiling above 325° C. under a pressure of about 12 millimeters is cracked into a fraction boiling between 350° C. under atmospheric pressure and 325° C. under a pressure of about 12 millimeters while the fraction boiling below 350° C. under atmospheric pressure is augmented at the most by about 10 per cent, and separating the reaction product in the enlarged reaction space into pitch and vapors substantially without release from pressure and substantially without cooling.

6. In the process claimed in claim 5 heating the initial material in the elongated heating zone in the presence of hydrogen sufficient in amount to prevent coking while heating and adding further hydrogen in an amount from about 0.2 to about 4 cubic meters per kilogram of initial material in the adjoining enlarged reaction space.
